UNITED STATES PATENT OFFICE.

RICHARD C. ULRICH, OF BOSTON, MASSACHUSETTS, ASSIGNOR TO WILLIAM FIRTH, OF SAME PLACE.

HUMIDIFIER.

SPECIFICATION forming part of Letters Patent No. 607,970, dated July 26, 1898.

Application filed August 7, 1897. Serial No. 647,477. (No model.)

To all whom it may concern:

Be it known that I, RICHARD C. ULRICH, of Boston, county of Suffolk, and State of Massachusetts, have invented an Improvement 5 in Humidifiers, of which the following description, in connection with the accompanying drawings, is a specification, like letters on the drawings representing like parts.

My invention is a humidifier or drosophore, 10 being an improvement on my previous invention disclosed in United States Letters Patent No. 572,780, the object of my present invention being to increase the spraying capacity of the humidifier and to decrease the 15 waste of the liquid thereby.

The details of my invention will be pointed out in the following description and the invention will be defined in the appended claims, reference being had to the accompanying drawings, illustrative of a preferred embodiment of my invention.

In the drawings, Figure 1 is a vertical section of my invention; and Fig. 2 is a transverse section thereof, taken on the line 2 2, 25 Fig. 1. Fig. 3 is a section similar to Fig. 2, showing a modification.

As herein shown, the humidifier is provided with an outwardly and downwardly flaring foot-flange *a*, resting on supports *a'*, projecting 30 radially from an inclined base *a²*, connected with a central cone *a³*, having an outlet *a⁴* at the lower end of the humidifier and a bail *b* at the upper end thereof, supporting a strainer *b'* and spray-nozzle *b²* of an inlet- 35 pipe *b³*, controlled by a valve *b⁴*, operated by a transverse arm *b⁵*, all as disclosed in my before-mentioned patent or of any other usual or preferred form.

In my above-mentioned patent the lower 40 and upper parts of the humidifier were connected by a cylindrical case having smooth walls. According to my present invention, however, I provide a case *c*, having various angularities, said case being herein shown as 45 vertically corrugated by similar corrugations *c'*, extending from the bottom to the top thereof. The effect of these angularities or corrugations is that when the umbellical

spray from the nozzle *b²* strikes the walls of the case *c* it is not only deflected downwardly, 50 as in my patented device, but it is separated by the inwardly-projecting ridges of the angular portions and deflected sidewise, as well as laterally, and the various portions thereof are given a multitude of directions, the spray 55 being separated and commingled to a degree hitherto unapproached. The result is that a large volume of spray in absolute suspension is driven forward, commingled with the air, which is sucked in thereby at the top of the 60 apparatus in the direction of the arrows *x x* and is driven forward and outward in the direction of the arrows *y* in a superior manner. Also by reason of the angular surfaces against which the spray impinges as it is driven from 65 the spray-nozzle there is a much larger volume of air drawn in at the upper end of the humidifier.

I do not restrict myself to the curved or undulating corrugations *c' c'* which I have 70 shown, inasmuch as various other forms of angular surfaces may be substituted therefor, the object being to separate and commingle the spray without condensing it or causing it to form in streams to trickle down 75 the case.

In order to isolate the angular or corrugated surface which receives the spray, and thereby overcome the sweating or condensing which would otherwise take place on the 80 outside of the case, I make said surface separate from and place it within the case, as shown at *c²*, Fig. 3.

Having described my invention, what I claim as new, and desire to secure by Letters 85 Patent, is—

1. A humidifier apparatus having a spraying device at its upper end and a spray-outlet at its lower end, combined with a casing between said spraying device and outlet, said 90 casing being vertically corrugated on its inner surface against which the spray may impinge, substantially as described.

2. A humidifier apparatus having a spraying device, a case and an outlet, combined 95 with a surface between said spraying device

and outlet against which the spray from the former is driven, said surface presenting to the spray a series of vertical corrugations, formed on a separate plate secured within 5 the case of the apparatus as and for the purpose set forth.

In testimony whereof I have signed my

name to this specification in the presence of two subscribing witnesses.

RICHARD C. ULBRICH.
